MACHINE FOR PRESSING SHEET MATERIAL

Robert Case Dennison, Manchester, Conn.

Application February 5, 1947, Serial No. 726,569

3 Claims. (Cl. 92—71)

1

This invention relates to a machine for compressing and surface finishing sheet material such as paper, paper board, leather and the like. The machine disclosed by way of example has been primarily contrived for compacting and glazing paper board, and such use will be referred to in discussing and describing the machine. It is to be understood, however, that such discussion and description is intended to be illustrative and that the calendering of paper and paper board, and the rolling of leather and other sheet material is contemplated.

A primary object of the invention is to provide a machine for producing a desired surface finish and density efficiently and dependably and at a high rate of output.

In accordance with a salient feature of the present invention, paper board or other sheet material is fed through successive roller couples, each consisting of an upper roller and lower roller having enlargements or collars provided at intervals, the widths of the collars, in the case of a two couple set, being substantially equal to the widths of the spaces between collars, and the upper and lower collars of a couple being matched and registered for bearing relation with one another.

The upper rollers of each couple are desirably fixed against upward movement, and a hydraulic piston is provided at each end of each lower roller for forcing the lower roller bearings upward. Adjustable stops for limiting upward movement of the bearings of the lower rollers determine the board gauge, causing an even and uniform product to emerge.

The first and second roller couples constitute a glazing or calendering set or unit, the first couple serving to compress and glaze the paper board along zones or stripes but leaving unglazed intervening zones or stripes of substantially equal width. The second couple acts similarly but serves to compress and glaze the areas which were missed by the first couple. Roller couples of a second pair bear a similar complementary relation to one another but have their collars offset somewhat with relation to the collars of the first pair.

The fact that each roller consists of a shaft with a series of spaced collars upon it, serves not only to enable the pressure per square inch to be increased by applying the same total pressure over a lesser area, but it also serves a further very important function. Bearings can be provided for each roller in the spaces between collars so that each roller is supported, backed up and re-

2

inforced at frequent intervals by a rigid bearing block. Sagging or yielding of the rollers is thus avoided, so that a very high pressure can be applied evenly over the work engaging areas of the rollers.

It is a feature of the invention that hydraulic pressure mechanism is provided below rather than above the rollers so that if any liquid escapes from a hydraulic cylinder it will not fall upon and soil the web nor be deposited upon a roller from which it might be transferred to the web.

As a further means for protecting the web or work sheets, brushes are provided at the introductory end of the machine and throats are provided for covering, protecting and guiding the web or work sheets to each of the successive roller couples. In addition to the protective function of the throats, the throats enable individual work sheets to be passed through the machine from couple to couple. The throats are also useful for facilitating the introduction of the leading end of a web into the machine.

Other objects and advantages will hereinafter appear;

25 In the drawing forming part of this specification

Fig. 1 is a view in sectional side elevation of a machine embodying features of the invention, the view being taken upon the line 1—1 of Fig. 2 looking in the direction of the arrows;

30 Fig. 2 is a sectional view taken upon the line 2—2 of Fig. 1 looking in the direction of the arrows;

Fig. 3 is a sectional view taken upon the line 3—3 of Fig. 2 looking in the direction of the arrows; and

35 Fig. 4 is a diagrammatic view showing the passage of a work web from a supply reel, past the brushes and the roller couples and onto a take-up reel.

40 Referring first to Fig. 4, it will be noted that the paper board or other sheet material 1 is drawn from a supply reel 2, is passed over an idler roller 3, thence between upper and lower rotary brushes 4 and 5 which travel counter to the travel of the web, and finally through successive roller couples 6, 7, 8 and 9 and onto a take-up reel 10.

45 The machine comprises a base 11 which provides a series of hydraulic cylinders 12 and 13, all of the cylinders at the left hand side of the machine, as seen in Fig. 3, being designated 12, and all of those at the right hand side being designated 13. Each cylinder is provided with a series of sealing or packing rings 16 and a threaded retaining ring 17.

The base further includes flanges 14 and 15 at the left and right sides of the machine, respectively. Through each of the flanges 14 and 15 a series of posts 18 extends, there being two of the posts mounted on each flange for each of the roller couples of the machine. Each post 18 comprises a reduced lower end portion 19, the lower extremity of which is threaded. The reduced portion is inserted through the flange with the shoulder at the upper extremity of the reduced portion bearing against the flange. The post is clamped firmly to the flange in an upright attitude by means of a clamping nut 20 which is threaded onto the protruding lower extremity of the post.

Above the flange the two posts of an adjacent pair extend through ears 21 of a bearing block 22. Each bearing block is engaged and operated by pistons 23 and 23a, which are located at opposite ends of the bearing block and are disposed, respectively, in the cylinders 12 and 13. The bearing blocks 22 are slideable upon the posts 18 being adapted to be urged upward by hydraulic pressure applied to the pistons in the cylinders 12 and 13. All of the cylinders communicate with a common source of liquid under pressure through main conduits 11c and branch conduits 11d, the admission and discharge of liquid being controlled for all cylinders by a single conventional valve mechanism (not shown).

The bearing block 22 carries the lower roller 25 of a roller couple. The roller 25 is a unitary roller, consisting of a continuous shaft 24 having a series of collars 24a provided upon it. The collars are of substantially the same width as the spaces between collars. The ends of the shaft and the portions of the shaft intervening between collars are all supported unyieldingly in axial alignment with one another by the bearing block. The bearing block provides lower half bearings for each of these bearing portions of the shaft, and a complementary half bearing 26 is provided in each instance, being clamped to the bearing block by bolts 27.

Upward movement of the bearing block 22, and hence of the roller carried by it, is limited by adjustable stop nuts 28 threaded on the respective posts 18. Lock nuts 28a, also threaded on the posts 18, fix the stop nuts 28 in desired positions.

The posts 18 have threaded upper end portions thereof screwed through upper bearing blocks 29, the posts being passed through ears 30 of the bearing blocks. Each bearing block 29 carries an upper roller 31 which is a unitary roller consisting of a continuous shaft 32 having a series of spaced collars 33. The shaft and collar construction is the same as that of the lower roller which has already been described, and the mounting of the upper roller in the bearing block 29 is the same as that of the lower roller in the bearing block 22. The bearing sections of the shaft at the ends of the shaft and in the spaces between successive collars are rotatably secured in axial alignment with one another, bearing block 29 providing half bearings, and complementary half bearings 34 being provided in each instance and secured to the bearing block through bolts 35.

Each bearing block 29 is normally supported in fixed position on the posts 18. Lock nuts 36 are threaded upon reduced upper end portions of the posts 18 and engage with the upper bearing blocks 29. The nuts are threaded right down into engagement with shoulders formed on the posts 18 so that the nuts form definitely located

stops for engagement with the bearing blocks 28.

When the lower bearing block 22 is urged upward by hydraulic pressure and there is no work sheet or web in the machine, the bearing block 22 stands in engagement with the stop nuts 28, and the bearing block 28 is held in engagement with the stop nut 36. The web or work sheet to be introduced is of greater thickness than the space intervening between the rollers 25 and 31. The width of this space is equal to the thickness to which the web or work sheet will be compressed by its passage through the couple. When the web or work sheet is passed through a roller couple with the pressure on, the zones or stripes acted upon are compressed. By readjustment of the nuts 28 the thickness to which the paper board will be compressed can be changed.

The description which has been given of the rollers and associated mechanism is equally applicable to any one of the roller couples and its bearing block. These couples differ from one another, however, in the disposition of the collars upon the rollers. The collars of roller couple 7 are complementary to the collars of roller couple 6. In other words, the stripes not compressed by roller couple 6 are compressed by roller couple 7, the combined effect of the two roller couples being to compress and glaze the web throughout the width thereof.

Roller couples 8 and 9 similarly constitute a complementary pair for giving the web or sheet a second pressing. The collars of couple 8 are not exactly aligned with the collars either of couple 6 or couple 7, and hence overlap the areas compressed by both of them. The rollers of couples 8 and 9 if desired may be arranged to compress the paper board thinner than the rollers 6 and 7 compress it. This result can be brought about by appropriate adjustment of the limit nuts 28 associated with the lower bearing blocks of roller couples 8 and 9.

Since the paper board is compressed by the roller couples 6 and 7, it is somewhat elongated and should be driven at a slightly higher peripheral speed by roller couples 8 and 9 than it is by the roller couples 6 and 7. The drive is to the upper rollers, and each upper roller drives the lower roller associated with it. The upper roller 31 having fast upon it a gear 41 which runs in driving engagement with a gear 42 fast upon the lower roller 23.

As best seen in Fig. 2, the upper roller of couple 6 is driven through a chain 43 and a sprocket 44. The drive is transmitted from the upper roller of couple 6 to the upper roller of couple 7 through sprockets 45 and 46 and a chain 47. The upper roller of couple 8 is driven through a chain 48a and a sprocket 48. The drive is transmitted from the upper roller of couple 8 to the upper roller of couple 9 through sprockets 49 and 50 and a chain 51. The sprocket 48 is driven at a slightly higher speed than the sprocket 44, consistent with the different thicknesses of the paper board as it emerges from the respective pairs of roller couples.

At the introductory end of the machine there is provided a pair of brackets 52 secured to the lower bearing block 22 of the first couple by bolts 53. These brackets carry upper and lower brushes 4 and 5 which are driven in the direction opposite to the travel of the web. The purpose of the brushes is to dust off and clean the web. Each upper bearing block 29 carries two angle brackets 56 upon which a guide plate 57 is secured. Each lower bearing block 22 carries two

angle brackets 58 upon which a guide plate 59 is secured. The guide plates 57 and 59 converge, forming a throat through which the web is guided to the associated roller couple. The first throat covers and protects the web and guides it from the brushes to the first roller couple 6. The next throat similarly covers, protects and guides the web from the roller couple 6 to the roller couple 7. The ensuing throats act in a similar manner.

The throats serve not only to protect the web but they serve to protect and to guide individual work sheets through the machine from roller couple to roller couple when it is desired to operate upon individual sheets rather than upon a web. The throats serve also to facilitate the introduction of the leading end of a work web into the machine. For example, the web can be first fed through the roller couples with the pressure on, the pressure can then be relieved, the web straightened, and the pressure reapplied.

By virtue of the arrangement described, and particularly by making up complementary roller couples so that each couple compresses and glazes only selected stripes, the pressure per unit area can be doubled or trebled or even further multiplied for a given total pressure depending upon whether two, three or more roller couples are provided to make up a single complementary set. Not only is the pressure concentrated, but by supporting the rollers at frequent intervals in the large rigid bearing blocks a very high pressure can be exerted and transmitted uniformly to the affected areas, there being no variation of pressure, of thickness, nor of surface quality resulting from sagging, bending or other yielding of the rollers.

The rate of production of the present machine is very much greater than the rates of output of the most rapid glazing machines known to the prior art.

I have described what I believe to be the best embodiments of my invention. I do not wish, however, to be confined to the embodiments shown, but what I desire to cover by Letters Patent is set forth in the appended claims.

I claim:

1. In a pressing machine for a work web or sheet of fibrous material, in combination, a set of roller couples, each couple composed of opposed, unitary rollers, and each unitary roller having a series of collars separated by bearing portions, the collars of the opposed rollers that form each couple being disposed in registering relation so that the work web or sheet is compressed along a series of stripes by each roller couple, and a rigid bearing structure for each roller, rigidly supporting the roller at its ends.

and in the bearing portions between its adjacent collars, the roller couples being disposed in complementary relation so that the entire work sheet or web is compressed by their conjoint action.

- 5 2. In a pressing machine for a work web of fibrous material, in combination, a pair of roller couples, each couple composed of opposed, unitary rollers, and each unitary roller having a series of collars separated by bearing portions, the collars of the opposed rollers that form each couple being disposed in registering relation so that the web is compressed by each couple along a series of stripes representing substantially half the total width of the web, a rigid bearing structure for each roller rigidly supporting the roller at its ends and in the bearing portions between its adjacent collars, the roller couples being disposed in complementary relation so that the entire web is compressed by their conjoint action.
- 10 3. A pressing machine for fibrous sheet material comprising, in combination, a roller couple including upper and lower rollers having series of cooperating collars separated from one another by bearings, a rigid upper bearing block in which all the bearings of the upper roller are rotatably secured in axial alignment with one another, a rigid lower bearing block in which all the bearings of the lower roller are rotatably secured in axial alignment with one another, power mechanism for urging one of the bearing blocks toward the other, said other bearing block being held firmly in a predetermined position against pressure exerted from the first through the rollers, and stop mechanism for limiting movement of the first bearing block toward the other to determine the uniform thickness to which the web will be compressed by the collars.
